UNITED STATES PATENT OFFICE.

LEO S. WHITEHEAD, OF AKRON, OHIO.

MACHINE FOR INSERTING WASHERS IN HEELS.

Application filed June 13, 1922, Serial No. 567,973. Renewed May 15, 1926.

This invention relates to mechanism for inserting washers in rubber heel slugs in the manufacture of rubber heels for boots and shoes.

5 The primary object of the invention is to provide a machine having automatically operating components that will pick up a predetermined number of washers and dispose them as a unit in a rubber heel slug, to 10 expedite the operation of introducing washers in rubber heel slugs with certainty as to application of all of the washers that may be required to be inserted in the slugs and with material advantages in view of the ordinary methods of manually picking up the 15 individual washers and inserting them in the slugs, and whereby often there are omissions, or the operators fail to fully equip each slug with the full number of washers 20 which it is adapted to receive. A further object of the invention is to provide a machine of the class specified of a comparatively simple organization requiring very little manual attention other than to replenish 25 the washers as the latter are used and to properly seat the heel slugs.

With these and other objects and advantages in view, the invention consists in the construction and arrangement of the several mechanisms and devices which will be more fully hereinafter described and claimed.

In the drawings:

Fig. 1 is a top plan view of a machine embodying the features of the invention;

Fig. 2 is a front elevation of the improved machine;

Fig. 3 is an end elevation;

Fig. 4 is a transverse vertical section on the line 4—4, Fig. 1;

Fig. 5 is a view similar to Fig. 4, showing the mechanism in different positions;

Figs. 6 and 7 are detail longitudinal sections through one of the gang of pick-ups and a portion of the washer-receiving bed or holder, Fig. 6 illustrating a part of the washer feeding means;

Fig. 8 is a detail sectional elevation of one of the washer pick-up devices and support therefor and a part of the washer holding and receiving bed;

Fig. 9 is an enlarged horizontal section on the line 9—9, Fig. 8;

Fig. 10 is an enlarged broken sectional view of a part of the washer feeding means and illustrating the operating devices therefor;

Fig. 11 is a horizontal section on a reduced scale on the line 11—11, Fig. 10;

Fig. 12 is a plan view of the washer-receiving bed or holder;

Fig. 13 is a section on the line 13—13, Fig. 12;

Fig. 14 is a longitudinal vertical section through the slug holding means showing one of the pick-ups seating a washer therein;

Fig. 15 is an enlarged transverse vertical section through one of the washer feeding units and showing one of the holding needles or pins for the washers in position therein and also illustrating a portion of the washer-receiving bed or holder in section; and

Figs. 16, 17, 18, 19, 20 and 21 are detail views of various parts of the mechanism.

The numeral 5 designates opposed frame uprights provided with lower outer angle supports or feet 6 and connected by tie-rods 7 arranged at intervals in such positions as to give the frame structure sufficient strength and also in part to serve as supporting means for parts of the mechanism which will be hereinafter explained. In addition to the tie-rods 7 the frame uprights

5 are connected by guide rods 8, and held by suitable forwardly projecting bracket members 9 is a table 10 having a front depending angular apron 11. Reciprocatingly mounted on the guide rods 8 is a carrier 12 having upper and lower pairs of forwardly

80 projecting arms 13 adjacent to opposite sides for vertical guide rods 14 having their ends secured in the said arms. On the vertical guide rods 14 is mounted a slide 15 for free vertical reciprocation. The slide 15 has rear-

wardly extending apertured arms 16 which 90 engage the rods 14, as clearly shown by Figs. 3, 4 and 5. A spring 17 is attached at its lower end to the upper part of the slide 15 and is adjustably secured at its upper end to a forwardly projecting arm 18 of an angle

95

100

bracket 19 secured to the rear of the carrier 12. The function of this spring 17 is to automatically pull the slide 15 upwardly when the latter is released from the influence of mechanism which operates to force the same downwardly. The slide 15 has a lower horizontally projecting plate 20 secured to bracket arm 21^a forming part of the said carrier or secured to the latter. The plate 20 performs the function of a plunger and carries a number of instrumentalities in the form of pick-ups 21 for engaging individual washers. The carrier 12 has a spring 22 attached to one side thereof and to the adjacent frame upright 5, and also attached to this carrier is a connecting rod 23 which passes through a slot 24 in the opposite frame upright 5 and is adjustably and movably attached or swiveled, as at 25, in the upper forked end 26 of an upright rocking lever 27, the latter lever being fulcrumed at its lower end to an extension of the angle foot 6, as at 28.

A drive shaft 29 extends through the frame uprights 5 and carries on one end a worm wheel 30 in continual mesh with a worm 31 on a transversely extending power-transmitting shaft 32 mounted in suitable bearings 33 secured to and projecting outwardly from the one frame upright 5. On the rear end of the shaft 32 is a pulley or analogous device 34 to which power from a suitable source is adapted to be transmitted. On the end of the shaft 29 opposite that carrying the worm wheel 30 a cam 35 is fixed and is of the face type, or has its outer face formed with a cam surface 36 including a low part 37 gradually inclining into a high part 38, and engaging this cam face 36 is a roller 39 carried on the rear end of a suitable shaft 40 fixed to the lever 27 at a suitable elevation above the lower fulcrumed end of said lever. The cam 35 operating on the roller 39 and through the connecting rod 23 will draw the carrier 12 towards the end of the machine at which the cam is located against the resistance of the spring 22 when the roller 39 engages the high part 38 of the cam face 36, and conversely, when the roller 39 engages the low part 37 of the said cam face 36, the carrier is released for retractive influence thereon by the spring 22, the said spring then operating to draw the carrier over into the position shown by Figs. 1 and 2.

The table 10 has a centrally located mold support 41 provided with a pedestal 42 adjustably mounted in a collar and opening 43 provided as a part of the table and formed in the latter, the adjustment of the pedestal and mold support or member 41 thereof being accomplished through a set screw or analogous device 44. The support 41 is so constructed as to removably receive a heel slug 45. In Fig. 4 of the drawings

the support 41 is shown as carrying a single heel slug, but it is to be understood that such support 41 may be constructed to hold any desired number of such heel slugs. The plunger plate 20 carrying the pick-up devices 21 is adapted to be normally disposed over and above the mold support 41 and heel slug 45, as shown by Fig. 2, for the purpose of automatically inserting in each heel slug a predetermined number of washers, certain movements and instrumentalities, herein-after described, causing a descent and elevation of the pick-up devices relatively to the heel slugs to accomplish the placement of the washers in the slugs. To the left of the mold support 41 a washer feeding and supplying mechanism is mounted and comprises an inverted U-shaped support 44^a with a flat top or table 45^a having thereon a plate 46 of the form shown in detail by Figs. 1, 12 and 13. The table member 45^a has a plurality of openings 47 formed therein with lower shouldered or enlarged portions 48, as clearly illustrated by Fig. 13, and the plate 46 has upper and lower circular seats 49 and 50 connected by straight slots 51, as shown by Fig. 12 in dotted and full lines, the lower seats or circular recesses being adapted to receive the washers simultaneously from the feeding means primarily carrying the washers, and the seats or recesses 50 providing the release means for the washers when in engagement with the pick-ups 21 depending from the plunger plate 20. From the foregoing it will be understood that the lower receptive seats or recesses 49 are offset relatively to the delivery or release seats or recesses 50, and the terminals of the slots 51 to the left are disposed in central relation to the lower receptive seats or circular recesses 49 which also at the right terminate centrally with relation to the delivery or release seats or recesses 50. By this means overhanging shoulders 52 are provided between the seats or circular recesses 49 and 50, so as to effect a straight sliding movement of each washer from the seat or recess 49 to the seat or recess 50. Secured to the bottom of the plate 46 are the horizontal shanks 53 (Fig. 15) of upwardly projecting spring jaws 54, these jaws extending upwardly through each seat or circular recess 49 and slightly converging towards their upper free ends so as to be spaced apart a less distance at the upper end than at the lower portion of said spring jaws. The distance between the lower portions of the spring jaws 54 is greater than the diameter of one of the washers 55 shown in Figs. 6 and 15, the said washers being of a standard size and of cup-shape, that is to say, each has a central depression 56 and a surrounding flange 57. The distance between the upper ends of the spring jaws 54 is less than the diam-

eter of the flanged portion 57 of the washers wardly from diametrically opposite portions and when a washer is pushed upwardly between the jaws 54, it engages the said jaws 58 and 59 as a unit have vertical movement within the tubular support 63, and this latter and spreads said jaws until the washer is elevated above the upper ends of the jaws, engaged by a spring 68 and having a wedge pin 69 extending centrally therethrough and adapted to extend through the washers when zontal position as shown by Figs. 6, 7 and 15. When the washers are positioned above support 63, the lower pointed or reduced 70 the upper ends of the spring jaws 54 in the end 70 of the wedge pin being always in circular recesses or seats 49, they are located position to engage between the upper ends close to the overhanging shoulders 52 provided by the slots 51 and may then be shifted 75 longitudinally from the circular recesses or seats 49 to the circular recesses or seats 50, 58 and 59 and tend to move said extremities and clear of the shoulders 52. A plurality 80 of washers 55, one in each recess 49, are all simultaneously elevated into the series of upper ends of the jaws and keep the latter 85 circular recesses or seats 49 and placed over centrally in position within the tubular support 63 and held elevated by the spring jaws 54, and port 63 for accurate operation by the said furthermore, all of the predetermined number of washers simultaneously so placed are 90 moved at one operation, or synchronously, from the circular seats or recesses 49 to the circular recesses or seats 50. Various means 95 may be employed for placing the washers 55, one in each recess 49, and the washers, when placed above are disposed over the plates 46 by movement and held by the spring jaws or holding devices 54, may be shifted simultaneously into the recesses or seats 50 by various forms of devices for this purpose, but it is preferred 100 to be in the form of pick-ups generally designated by the numeral 21, hereinbefore referred to.

The pick-ups 21, as hereinbefore explained, are carried by a plunger or plunger plate 20 and are arranged in a gang corresponding in number to the maximum number of recesses 49 and 50 and slots 51 formed in the plate 46, the latter plate constituting the receptive holding means for the predetermined number of washers adapted to be picked up and inserted in the heel slugs. 105

A preferred construction of the pick-up devices and the operation of the same is shown by Figs. 6, 7, 8 and 9, and the operation thereof relatively to a slug is further illustrated by Fig. 14. Each pick-up device 110 comprises a pair of pivoted jaws 58 and 59 having lower reduced tapered ends 60 with a groove or circumferential seat 61 above said ends. Each pair of pivoted jaws is pivoted to a tubular head 62 mounted in the lower end of a depending tubular support 63, the lower tapered ends 60 of the jaws being normally open or separated and closed by spreading the upper ends 64 of the jaws. 115

The tubular head 62 to which the jaws are pivoted has a vertical sliding movement relatively to the depending tubular support 63, the latter having diametrically opposed slots 65 in which pins 66 projecting out-

wardly from diametrically opposite portions of the said head move. By this means the jaws 58 and 59 as a unit have vertical movement within the tubular support 63, and this movement is against a flanged washer 67 70 engaged by a spring 68 and having a wedge pin 69 extending centrally therethrough and adapted to extend through the washers when delivered to the upper end of the tubular support 63. The upward unitary movement of the jaws, as above indicated, is against the resistance of the spring 68, the latter 75 moved at one operation, or synchronously, from the circular seats or recesses 49 to the circular recesses or seats 50, 58 and 59 and tend to move said extremities and clear of the shoulders 52. A plurality 80 of washers 55, one in each recess 49, are all simultaneously elevated into the series of upper ends of the jaws and keep the latter 85 circular recesses or seats 49 and placed over centrally in position within the tubular support 63 and held elevated by the spring jaws 54, and port 63 for accurate operation by the said furthermore, all of the predetermined number of washers simultaneously so placed are 90 moved at one operation, or synchronously, from the circular seats or recesses 49 to the circular recesses or seats 50. Various means 95 may be employed for placing the washers 55, one in each recess 49, and the washers, when placed above are disposed over the plates 46 by movement and held by the spring jaws or holding devices 54, may be shifted simultaneously into the recesses or seats 50 by various forms of devices for this purpose, but it is preferred 100 to be in the form of pick-ups generally designated by the numeral 21, hereinbefore referred to.

The pick-ups 21, as hereinbefore explained, are carried by a plunger or plunger plate 20 and are arranged in a gang corresponding in number to the maximum number of recesses 49 and 50 and slots 51 formed in the plate 46, the latter plate constituting the receptive holding means for the predetermined number of washers adapted to be picked up and inserted in the heel slugs. 105

A preferred construction of the pick-up devices and the operation of the same is shown by Figs. 6, 7, 8 and 9, and the operation thereof relatively to a slug is further illustrated by Fig. 14. Each pick-up device 110 comprises a pair of pivoted jaws 58 and 59 having lower reduced tapered ends 60 with a groove or circumferential seat 61 above said ends. Each pair of pivoted jaws is pivoted to a tubular head 62 mounted in the lower end of a depending tubular support 63, the lower tapered ends 60 of the jaws being normally open or separated and closed by spreading the upper ends 64 of the jaws. 115

The tubular head 62 to which the jaws are pivoted has a vertical sliding movement relatively to the depending tubular support 63, the latter having diametrically opposed slots 65 in which pins 66 projecting out-

wardly from diametrically opposite portions of the said head move. By this means the jaws 58 and 59 as a unit have vertical movement within the tubular support 63, and this movement is against a flanged washer 67 70 engaged by a spring 68 and having a wedge pin 69 extending centrally therethrough and adapted to extend through the washers when delivered to the upper end of the tubular support 63. The upward unitary movement of the jaws, as above indicated, is against the resistance of the spring 68, the latter 75 moved at one operation, or synchronously, from the circular seats or recesses 49 to the circular recesses or seats 50, 58 and 59 and tend to move said extremities and clear of the shoulders 52. A plurality 80 of washers 55, one in each recess 49, are all simultaneously elevated into the series of upper ends of the jaws and keep the latter 85 circular recesses or seats 49 and placed over centrally in position within the tubular support 63 and held elevated by the spring jaws 54, and port 63 for accurate operation by the said furthermore, all of the predetermined number of washers simultaneously so placed are 90 moved at one operation, or synchronously, from the circular seats or recesses 49 to the circular recesses or seats 50. Various means 95 may be employed for placing the washers 55, one in each recess 49, and the washers, when placed above are disposed over the plates 46 by movement and held by the spring jaws or holding devices 54, may be shifted simultaneously into the recesses or seats 50 by various forms of devices for this purpose, but it is preferred 100 to be in the form of pick-ups generally designated by the numeral 21, hereinbefore referred to.

The pick-ups 21, as hereinbefore explained, are carried by a plunger or plunger plate 20 and are arranged in a gang corresponding in number to the maximum number of recesses 49 and 50 and slots 51 formed in the plate 46, the latter plate constituting the receptive holding means for the predetermined number of washers adapted to be picked up and inserted in the heel slugs. 105

A preferred construction of the pick-up devices and the operation of the same is shown by Figs. 6, 7, 8 and 9, and the operation thereof relatively to a slug is further illustrated by Fig. 14. Each pick-up device 110 comprises a pair of pivoted jaws 58 and 59 having lower reduced tapered ends 60 with a groove or circumferential seat 61 above said ends. Each pair of pivoted jaws is pivoted to a tubular head 62 mounted in the lower end of a depending tubular support 63, the lower tapered ends 60 of the jaws being normally open or separated and closed by spreading the upper ends 64 of the jaws. 115

The tubular head 62 to which the jaws are pivoted has a vertical sliding movement relatively to the depending tubular support 63, the latter having diametrically opposed slots 65 in which pins 66 projecting out-

traversed the high part 38 of the cam 35, and the spring 22 instantly operates to shift the carrier 12 to the right, or normal position. The movement of the carrier is so rapid that the washers 55 are all instantly lifted from the upper ends of the spring jaws 54 and shifted under the shoulders 52 to the right into the release recesses or seats 50 and then upwardly through the latter clear of the plate 46 and are carried over the heel slug 45 and all simultaneously inserted by a further depressing unitary movement of the pick-ups 21 into the rubber slug, as shown by Fig. 14. The rubber slugs in which the washers are inserted are preliminarily prepared prior to disposition on the mold support 41 by having suitable openings 72 formed therein and extending partially through the same as shown by Fig. 14, the said openings being of less diameter than the maximum diameter of the washers 55 inserted therein, and after the washers are seated in these openings of the slugs, they are held with sufficient resistance to permit the ready withdrawal of the lower tapered ends 60 of the jaws 58 and 59, the said tapered ends at this time being closed in view of the downward pressure exerted on the pick-up units and the operation of the wedge pins 69 with relation to the upper ends 64 of the jaw units as hereinbefore explained. The closure or contraction of the lower tapered ends 60 of the jaws 58 and 59 of the pick-up units permits the latter to be readily elevated to the normal position shown by Fig. 2 and ready for further operation in conjunction with the plate 46, the elevation of the pick-ups 21 into normal position taking place immediately prior to a further shifting of the carrier 12 to the left through the operation of the mechanism including the cam 35 and and roller 39 hereinbefore described.

It is obvious that means must be provided for supplying the plate 46 with washers at regular intervals, and it is proposed to use any organization of devices adapted for this purpose. One preferred organization of cooperating devices, however, is shown in the drawings and particularly by Figs. 3, 4, 5, 10, 11, 13 and 15. The essential element of this feeding mechanism is a reciprocating rod or elongated pin 73 upon which the washers 55 are mounted, the washers all being disposed with their concave sides uppermost, and in the preparation of the machine for operation, each rod or pin 73 will be filled uniformly to the upper end thereof. The number of rods or pins 73 employed will be equal to the number of recesses or seats 49 and 50 formed in the plate 46, and these recesses 49 and 50 as well as the rods or pins 73 may be varied in accordance with the number of washers desired to be inserted in each rubber heel slug. The operation of

the rods or pins 73 must also be such that they will first elevate the stack of washers thereon and deliver one washer from each into position for holding engagement by the jaws 54, the stroke of each rod or pin 73 being so regulated that only one washer 55 may be disposed on the upper ends of the spring jaws 54 by each upward thrust of each of the rods or pins. It is also necessary to provide means for compensating for the gradual diminution of the number of washers 55 on each rod or pin 73, and moreover, to provide for a variation of the number of washers on each rod or pin so that there may be at all times a regularity of feed or delivery of the washers to the plate 46 and the spring jaws 54 of the latter. All of the rods or pins 73 have a similar mounting and operation, and a detail description of one will, therefore, suffice for all. Each rod or pin 73 is secured to a reciprocating tube or tubular housing 74 by means of a removable screw 75, which under certain conditions will permit the rod or pin to be withdrawn from the tube. The lower end of the tube 74 is secured to a reciprocating support 76, the said lower end of the tube 74 extending fully through the support as shown by Fig. 15, so that each tube 74 may be movably mounted over a guide tube 77 secured at its lower end to an adjusting foot plate 78. Each tube 74 has free movement through an opening 79 formed in the table 10, this opening also receiving the lower end of a tubular upright 80, which also engages the lower shouldered or enlarged portion 48 of one of the openings 47 in the table member 45^a which carries the plate 46. The plurality of tubular uprights 80 provide for the necessary strength or rigidity between the table 10 and the table member 45^a, and at the same time serve as tubular housings for the operation of the tubes 74 and rods or pins 73 therethrough. The upper end of each guide tube 77 has a centrally apertured cap 81, and cooperating with and projecting upwardly from the cap and the upper end of the tube 77 is a washer plunger consisting of a tubular shank 82 of reduced diameter having an upper flanged head 83 on which the washers are disposed, the lowermost washer of each stack bearing on the said head 83. The centrally apertured cap 81 at the upper end of the guide tube 77 moves over the shank 82, but the lower end of this shank is screw-threaded and has a retaining screw collar or ring nut 84 which prevents separation of the lower extremity of the said shank 82 from the cap 81 and the upper end of the guide tube 77. Surrounding the shank 82 is a spring 85 against the lower end of which the cap 81 has bearing engagement, the upper end of the spring engaging the flanged head 83 of the plunger. The spring 85 provides for a

cushioning operation as well as an adjustment to compensate for variation of the number of washers that are supported by the head 83 as the said washers are gradually fed to the jaws 54 above and in accordance with the adjustment of the foot plate 78 in a manner which will be presently explained. The guide tube 77 has a longitudinal slot 86 therein through which the screw 75 extends so as to permit reciprocation of the tube 77 and the rod or pin 73 without restriction. Thus, as the guide tube 77, through its foot plate 78, is gradually adjusted to compensate for a diminution of the number of washers on the rod or pin 73 and is correspondingly elevated in the lower extremity of the tube 74, the screw 75 will move lengthwise of the slot 86 to permit such movement or adjustment. When the rod or pin 73 carrying the washers 55 is moved upwardly between the jaws 54 to deliver and place individual washers on the jaws, the upper extremity of the tube 74 moves into the enlarged portion 48 of the opening 47 in the table member 45; therefore, and the rod or pin 73 projects upwardly through the center of the receiving recess or seat 49 and slot 51 which connects said recess or seat with the recess or seat 50, far enough to insure a positive placement of each washer 55 on the upper ends of the spring jaws 54. This upward movement of each rod or pin 73 takes place during the time that the pick-ups 21 are located over and operating in conjunction with the mold supporting table 41. Extending through the reciprocating support 76 and the adjusting foot plate 78 are a pair of guide rods 87 which depend from the table 10 as shown by Figs. 4, 5 and 10 and are secured against a tie plate 88 located below the adjusting foot plate 78. These guide rods 87 are located at opposite sides of the vertical center of this washer supply and feeding mechanism, openings 89 being formed in the plate 78 of such diameter as to permit the latter plate to move upwardly and downwardly over the said guide rods, and in the reciprocating support 76 are bearing bushings 90 through which the guide rods 87 extend. At the rear central edge portion of the tie plate 88 a bearing 91 is formed and is of greater thickness than the said tie plate, and therein a vertical adjusting shaft or spindle 92 is mounted, the latter shaft having a lower reduced extremity 93 rotatable in and extending through the bearing 91 and depending below the plate 88 a sufficient distance to receive a small band pulley 94. The adjusting shaft or spindle 92 by the formation of the lower reduced extremity 93 is provided with a shoulder 95 which engages the upper side of the bearing 91 and is thereby sustained in its desired vertical projection relatively to the bearing 91 and plate 88. Surrounding the shaft or spindle 92 is a fixed adjusting sleeve 96 secured to the said shaft or spindle by a spline or analogous key 97 and having the outer surface formed with relatively fine screw threads 98. The upper end of the sleeve 96 is flanged, as at 99, and mounted in a seat 100 in the center of the lower side of the reciprocating support 76 and is secured to the said support by an annular plate 101.

Both the shaft or spindle 92 and the adjusting sleeve 96 extend through the adjusting foot plate 78, the latter having an adjusting means seated therein. The adjusting means consists of two opposed block sections 102 and 103 having semicircular screw-threaded recesses 104 in the inner opposing edges thereof which conjointly engage the threads 98 of the sleeve 96. The block sections 102 and 103 are longitudinally shiftable in a seat opening 105 formed in the center of the adjusting foot plate 78 and each has a pair of outwardly projecting rods 106 secured thereto and movable through the plate 78, the outer ends of these rods being connected by cross heads 107 for unitedly operating the said rods. Projecting outwardly from the centers of the opposite end edges of the plate 78 are screw stems 108, the inner ends of these stems being fast in the plate 78. The screw stems 108 also extend through tubular screw-threaded shanks 109 of thumb nuts or analogous devices 110, the said shanks 109 being swiveled in the cross heads 107, so that by turning these nuts 110 the cross heads 107 with their pairs of rods 106 will be drawn outwardly or forced inwardly in accordance with the direction of rotation of the thumb nuts 110, to correspondingly shift the block sections 102 and 103. The object of this adjusting means cooperating with the threaded sleeve 96 is to permit the adjusting foot plate 78 and the guide tubes 77 secured thereto to move upwardly as the charges of washers 55 on the rods or pins 73 become exhausted and to enable said pins to be recharged or replaced by other similar rods or pins having thereon the maximum number of washers the said rods or pins are adapted to carry. This replenishment or recharging of the feeding means with washers will be required only at comparatively long intervals, in view of the fact that each rod or pin is long enough to carry a large number of the washers, and for conveniently charging the feeding mechanism with washers, it is proposed to have the rods or pins 73 removable from the devices carrying the same, and especially from heads 111 on the lower ends thereof and which are directly engaged by the adjusting screws 75. The washer receiving bed or holder plate 46 may be easily removed, the said bed or holder plate being secured in place by screws 1120 1225 1300

112 that are readily accessible from the top of the bed or holder plate (see Figs. 12 and 13). After the bed or holder plate 46 is removed, the rods or pins 73 in loaded condition may be inserted downwardly through the tubes 74 and re-engaged with the heads 111 therefor, and subsequently the bed or holder plate 46 may be replaced and secured with very little delay in the 10 charging operation. It is obvious that the proportions of the several parts, and particularly the length of the rods or pins 73, may be such that the quantity of washers on each pin may be sufficient to render the rods or pins operative in placing washers for disposal in several hundred heel slugs before it will become necessary to recharge the washer feeding mechanism with washers.

20 On the drive shaft 29 is a substantially elliptical cam 113, a band pulley 114 and an irregular cam 115. The elliptical cam 113 has a large portion 116 thereof concentric with the shaft 29, into which merges the opposite terminals of a crescent-shaped enlargement or high part 117, as shown by Fig. 18. The irregular cam 115 has the greater portion thereof, as at 118, concentric with the shaft 29, and in alinement with one 25 diameter of the said shaft the cam 115 is formed with a cam rib 119 extending full length thereof. In the opposite portion of the said cam 115 a high part or cam projection 120 is formed of sufficient dimensions to provide for the motion which will be presently explained and having abrupt side portions 121 continuing into the portions 118 concentric with the shaft 29. The cam 113 controls the reciprocation of the 30 washer feeding mechanism and its change of movement relatively to the said feeding mechanism is accomplished through the medium of links 122 secured at their upper ends to apertured bosses 123, one of 35 which is shown by Fig. 10 and secured to or forming part of the reciprocating support 76. The lower ends of the links 122 are connected to the arms 124 of the front bifurcated extremity 125 of a rocker arm 40 126 having an intermediate bearing 127 adapted to engage one of the tie rods 7. The rear end of the rocking arm 126 is enlarged and bifurcated, as at 128, and carries a roller 129 therein which is adapted 45 to contact with the periphery of the cam 113. When the roller 129 engages the portion 116 of the cam 113 concentric with the shaft 29, the front end of the rocker arm 50 is lowered and the reciprocating support 76 is pulled downwardly to its normal position through the links 122, and therewith descend the tubes 74 and rods or pins 73 together 55 with the cushioning tubes or washer plungers having the tubular shanks 82 and heads 60 83.

When the high part 117 of the cam 113 engages the roller 129, the rear extremity of the arm 126, or that portion in rear of the rod 7, is depressed and the forward extremity or member of said rocking lever is elevated, thereby raising the reciprocating support and the parts associated therewith for vertical movement, so as to bring the washers on the upper ends of the rods or pins 73 into engagement with the spring jaws 54 75 and place a washer 55 above each pair of said spring jaws, as hereinbefore explained. After this placement, a lowering action of the reciprocating support and parts associated therewith for vertical movement again 80 ensues. The rotation of the pulley 94 on the lower end of the shaft or spindle 92 for actuating the screw-threaded feed sleeve 96 is accomplished through the medium of a crossed belt 130 which is also trained over 85 a pulley 131 mounted on a motion transmitting shaft 132 having suitable bearing in angularly depending bracket arms 133 secured to the rod 7 on which the rocker arm 126 is mounted. On the shaft 132 a band 90 pulley 134 is also carried and is of materially greater diameter than the band wheel or pulley 131, the pulley 134 having a belt 135 trained thereover and over the pulley 114 on the shaft 29 between the cams 113 and 95 115. The proportions of this driving mechanism and the threads 98 of the sleeve 96 is such that one complete revolution of the shaft 29 will feed the sleeve 96 vertically the 100 distance of one thread and correspondingly raise the reciprocating support 76. The distance feed of one thread 98 of the sleeve 96 corresponds to the thickness of one washer, and hence, as each washer is removed from the several rods or pins 73, the compensation for difference of vertical extent of the stacks of washers on the several rods or pins 73 is provided for by the screw-threaded sleeve or automatic regulator 96.

The arrangement of the shaft 132 and 110 pulleys 131 and 134 is clearly shown in detail by Fig. 17, and the relative arrangement of the cams 113 and 115 and the pulley 114 is illustrated by Fig. 16. It should be understood that care will be taken in determining the proportions or ratio of all of the moving parts, and especially those for actuating the pulley 94, to provide for the compensating feed of the threaded sleeve 96 to accommodate the difference in the heights of 115 the stacks of the washers on the rods or pins 73, to always bring the uppermost washer of all stacks in proper elevated positions for practical feed thereof between the groups of spring jaws 54 and disposition 120 of washers on the jaws for subsequent engagement by the pick-ups 21.

The cam 115 particularly controls the rise and fall of the pick-ups 21 and said cam is elongated, or has a length propor-

tionate to the movement of the carrier 12 through the operation of the roller 39 on the cam 35. The plunger plate 20 is vertically reciprocated through the medium of a connecting rod 136 movably attached to the rear thereof between the guide rods 14, said connecting rod 136 being also movably attached at its lower end to a rocking arm 137 fulcrumed to a rear angularly depending bracket arm 138 forming a part of the carrier 12. The rear extremity of the rocking arm has a roller 139 mounted therein, said roller always being held in position to engage the periphery of the cam 115. The roller 139 not only engages the periphery of the cam 115, due to the rotation of said cam, but also moves longitudinally over the said cam proportionately to the reciprocation in reverse directions of the carrier 12.

When the roller 139 of the rocking arm 137 engages the opposite portions 118 of the cam 115 concentric with the shaft 29, the plunger 20 carrying the pick-ups 21 is in elevated position, or is freed for action of the spring 17, which always tends to pull the said plunger or plunger plate 20 upwardly. When the roller 139 engages the cam boss or projection 120, the rear extremity of the rocking arm 137 with the roller 139 is elevated and the opposite extremity of the said lever is lowered or depressed and pulls the plunger or plunger plate 20 downwardly through the connecting rods 136 against the resistance of the spring 17.

At the time that the roller 139 engages the periphery of the cam boss or projection 120, the plunger or plunger plate 20 with the pick-ups 21 will be over the washer-receiving bed or holder 46 and the pick-ups depressed into the slots 51, and the said pick-ups will remain in this depressed position as long as the roller 139 engages the periphery of the said projection or boss 120. This cam projection or boss is so proportioned as to maintain the pick-ups depressed relatively to the washer-receiving bed or holder 46 until the washers are removed from the several pairs of spring jaws 54 and shifted into the release recesses or seats 50, the longitudinal movement of the pick-ups from the left to the right extremity of the slots 51, or from over the receiving recesses or seats 49 to the release recesses or seats 50, being due to the movement of the carrier 12. This movement of the carrier to the right ensues just as the roller 39 passes off the high part 38 of the cam 35 to the low part 37 of the said cam, such change of engagement of the roller 39 ensuing immediately after the lower tapered ends 60 of the jaws 58 and 59 of the several pick-ups have engaged the washers held by the spring jaws 54. When the roller 139 moves off the cam boss or projection 120, the action is sudden in view of the quick

drop at the adjacent side edges 121 of the said cam projection, and as a consequence, all of the pick-ups will be instantly elevated by the action of the spring 17 on the plunger or plunger plate 20.

As hereinbefore indicated, the movement of the carrier 12 continues to the right until the pick-ups 21 are positioned over the mold supporting table 41, and at such time the cam 115 will have rotated sufficiently to bring the cam rib 119 in position for engagement by the roller 139, and as the latter roller engages and passes over the rib 119, the plunger or plunger plate 20 with the pick-ups carrying the washers are suddenly depressed into the openings formed in the rubber slug thereover and the washers set in place as shown by Fig. 14. As soon as the washers are set by the pick-ups, the cam rib 119 will have been passed by the roller 139 and instantly the plunger or plunger plate 20 will again be elevated by the spring 17, and as the plunger or plunger plate 20 starts to rise, the lower tapered ends 60 of the jaws 58 and 59 of the respective plungers will be closed and thereby reduced in diametrical extent and be readily withdrawable from the central openings of the washers. By this means the washers will be left firmly and positively associated with and secured in the heel slug. At the time that the pick-ups are making their sudden descent to place the washers in the heel slug, the washer feeding mechanism will be operating to again dispose washers on the upper converged extremities of the spring jaws 54 for subsequent engagement by the pick-ups in the manner just explained. These operations will be regularly continued in sequence, and as the operation of disposing washers in one heel slug is completed and the pick-ups have been elevated, another heel slug is placed in position for reception of the washers.

From the foregoing the operation of the mechanism will be readily understood, and it will be seen that washers may be rapidly and automatically placed and secured in heel slugs in accordance with a predetermined number, and the mechanisms for feeding the washers into position for pick up and the pick up devices themselves will uniformly operate to load a heel slug with washers with certainty, or in such manner that each opening in the slug to receive a washer will be supplied with a washer. Any suitable mechanism may be employed for preparing the rubber slugs and forming the openings or seats therein for reception of the washers, and also any suitable means may be provided for facilitating the positioning of the slugs under the pick-ups to receive the washers and subsequently for removing the loaded slugs from the machine, such means not being essential in the operation of the pres-

ent improved machine and capable of extensive variation. The important features of the invention reside in the means for placing the washers in position to be picked up by mechanical devices, as specifically hereinbefore explained, and successively conveyed to a point for insertion in rubber slugs, the whole operation being automatically effected without requiring hand manipulation of the washers.

What is claimed as new is:

1. In a machine of the class specified, means for feeding and placing washers in a predetermined group, means for holding a heel slug, and means for picking up, transferring and inserting the said washers simultaneously in the heel slug.

2. In a machine of the class specified, means for disposing a predetermined number of washers in an accessible group, means for holding a heel slug, and means for transferring the washers over and inserting them in the heel slug.

3. In a machine of the class specified, means for holding a heel slug, mechanism in part automatically movable over the slug and comprising a carrier for holding a predetermined number of washers, and devices for inserting the washers in the slug.

4. In a machine of the class specified, means for holding a slug, carrying means automatically chargeable with a predetermined number of washers and automatically movable over the slug, and means co-operating with the said carrying means for simultaneously inserting the washers held by the latter in the slug.

5. In a machine of the class specified, means for holding a predetermined number of washers in position for insertion in a heel slug, means for holding a heel slug, and means for engaging, transferring and simultaneously inserting the washers in the slug.

6. In a machine of the class specified, means for holding a heel slug and means for automatically picking up and holding a predetermined number of washers and movable over the said slug and also for simultaneously inserting the said predetermined number of washers in the slug.

7. In a machine of the class specified, means for holding a heel slug having washer-receiving openings formed therein, and automatically movable devices for carrying washers corresponding in number to the openings in the slug and for simultaneously and automatically inserting the washers in the slug in flatwise position and permitting the material of the slug to close against and hold the washers in place therein.

8. In a machine of the class specified, means for supporting a heel slug of yieldable material having washer-receiving openings therein, means for holding a predetermined number of washers in uniform horizontal positions and automatically movable over the slug, and means for automatically inserting the washers in horizontal position in the openings of the slug.

65

9. In a machine of the class specified, means for supporting a slug, means for holding a predetermined number of washers in accessible positions, a reciprocating carrier mounted to move longitudinally of the machine from the slug-supporting means to the washer-holding means and then return to the slug-supporting means, and a vertically movable plunger means forming part of the carrier having pick-up devices to engage the washers and insert them in the slug.

70

9. In a machine of the class specified, means for supporting a slug, means for holding a predetermined number of washers in accessible positions, a reciprocating carrier mounted to move longitudinally of the machine from the slug-supporting means to the washer-holding means and then return to the slug-supporting means, and a vertically movable plunger means forming part of the carrier having pick-up devices to engage the washers and insert them in the slug.

75

10. In a machine of the class specified, means for supporting a heel slug, a washer receiving bed for holding a predetermined number of washers, means for regularly supplying the washers to the bed and transferring means including a vertically reciprocating gang of pick-ups for engaging the washers and disposing them over and inserting them in the slug.

80

10. In a machine of the class specified, means for supporting a heel slug, a washer receiving bed for holding a predetermined number of washers, means for regularly supplying the washers to the bed and transferring means including a vertically reciprocating gang of pick-ups for engaging the washers and disposing them over and inserting them in the slug.

85

11. In a machine of the class specified, means for supporting a heel slug, a washer receiving bed for holding a predetermined number of washers in accessible positions, reciprocating rods for supplying the bed with washers, compensating means cooperating with the rods to always place the washers in supplying positions on the rods irrespective of the number of washers on the rods, and means for transferring the washers from the bed and inserting them in the heel slug.

90

11. In a machine of the class specified, means for supporting a heel slug, a washer receiving bed for holding a predetermined number of washers in accessible positions, reciprocating rods for supplying the bed with washers, compensating means cooperating with the rods to always place the washers in supplying positions on the rods irrespective of the number of washers on the rods, and means for transferring the washers from the bed and inserting them in the heel slug.

95

12. A machine for loading rubber heel slugs with washers, including means for feeding and placing washers in a predetermined group, means for holding a rubber heel slug, and movable means for engaging and inserting the said washers simultaneously in the heel slug.

100

12. A machine for loading rubber heel slugs with washers, including means for feeding and placing washers in a predetermined group, means for holding a rubber heel slug, and movable means for engaging and inserting the said washers simultaneously in the heel slug.

105

13. A machine for loading rubber heel blanks with washers, comprising a support for the blank, and a plunger for forcing a washer flatwise into the blank, said plunger being constructed to permit the material of the heel blank to squeeze inwardly around the edge of the washer after it has been imbedded in the blank to hold the washer in the blank during and after the withdrawal of the plunger.

110

13. A machine for loading rubber heel blanks with washers, comprising a support for the blank, and a plunger for forcing a washer flatwise into the blank, said plunger being constructed to permit the material of the heel blank to squeeze inwardly around the edge of the washer after it has been imbedded in the blank to hold the washer in the blank during and after the withdrawal of the plunger.

115

14. In a machine for loading rubber heel blanks with washers, the combination of a washer carrier having a number of washer-receiving openings therein corresponding in number and arrangement to the number and arrangement of the washers to be imbedded in each blank, plungers movable in said openings for forcing the washers simultaneously into the blank, washer feeding mechanism operating automatically to deliver a washer to each plunger, and means

for supporting a rubber heel blank in position for the operation thereon of said plungers.

15. In a machine for imbedding washers in a rubber heel blank, the combination of blank-supporting means, a washer supply means, means automatically movable between the washer supply means and the blank for carrying a predetermined number of wash-

ers for disposition in the blank, and means 10 for simultaneously disposing the washers in the blank in flatwise condition, the washers being directly engaged by the material of the blank to hold them positively in place in the blank. 15

In testimony whereof I have hereunto set my hand.

LEO S. WHITEHEAD.
